JOSEPH STOTT, OF WORCESTER, AND WILLIAM STOTT, OF SHREWSBURY, MASSACHUSETTS.

PICKING-MOTION FOR LOOMS.

1,194,898.

Specification of Letters Patent. Patented Aug. 15, 1916.

Application filed October 11, 1915. Serial No. 55,152.

To all whom it may concern:

Be it known that we, JOSEPH STOTT and WILLIAM Stott, citizens of the United States, residing at Worcester and Shrewsbury, county of Worcester, State of Massachusetts, have jointly invented a new and useful Picking-Motion for Looms, of which the following is a specification.

The principal object of this invention is

- 10 to provide a simplified form of picking motion of a more durable character than those now in use; also to provide a construction in which the motion which corresponds most nearly with the usual picker stick motion shall
- 15 be performed by a lever which does not have any solid means secured to it that directly engages or operates the shuttle so that the shock of operation will not be transmitted directly to this member; also to provide im-
- 20 proved means whereby the shuttle is ejected positively and the lever for causing this operation returned to normal position yieldingly and in which the shuttle ejecting operation can be performed readily and more
- 25 than once during each operation of the actuating shaft without providing the same with any complicated cam or crank system; and to provide a practical and durable form of flexible actuating means for the shuttle.
- 30 Reference is to be had to the accompanying drawing which is a perspective view of a preferred form of this invention capable of being applied to a loom but shown without reference to any particular type of loom.
- 35 We are aware of the fact that flexible members have been proposed for use in picking motions, but so far as we are aware they have usually been complicated either by unnecessary springs or complication has been in-
- 40 troduced by trying to make one actuating means control the picking motions of both ends of the loom. It is very largely for the purpose of simplifying mechanism employing this principle and at the same time re-
- 45 taining the advantageous features thereof that this invention is made.

Referring to the drawing it will be seen that a shaft 10 is shown. This may be the usual actuating shaft of the loom if desired or it may be located at some other convenient position. On this shaft is a head 11 fixedly secured to the shaft and provided preferably with a plurality of rollers 12 or other means for engaging the end of a lever 13 and actuating it. This lever is pivoted on

a stud 14 parallel with the shaft 11 so that the lever 13 is in a plane perpendicular to the length of the shuttle box 15 and oscillates in that plane. This lever is provided with a spring 16 yieldingly holding it down and with an adjustable stop 17 which limits its downward motion, in this case being shown as resting on a plate 18 for that purpose.

For the purpose of operating the shuttle a flexible connection 20 in the form of a rope, chain or belt is shown. This passes under a pulley 21 over two pulleys 22 and 23 and around a fourth pulley 24. These pulleys are arranged substantially in the same plane, the pulleys 22 and 23 being off-set from each other just enough to avoid interference of the different strands of the flexible connection or belt 20. This plane is perpendicular to the plane in which the lever 13 oscillates.

The two pulleys 23 and 24 are arranged at substantially the same height so as to cause the upper strand of the belt 20 to reciprocate in a direction parallel with the length of the shuttle box. The lower strand is shown also substantially parallel with this but that is not essential. The two ends of the belt coming down over these pulleys pass down substantially vertically and the one of them which passes over the pulley 22 is connected directly with the operating end of the lever 13. The other one passes down below this end and up around the pulley 20 so that it extends upwardly to the end of the lever 13 to which it is secured.

Fixed on the upper strand of the belt 20 is an L-shaped plate 25 to which is fixed a picker 26 which may be of the usual raw hide construction. This plate 25 is preferably of sheet metal and guided by the picker rod 27 in the usual position. The end of the picker is adapted to engage the shuttle 30 and eject it from the box.

The operation of the device will be obvious from what has been said and it is as follows:—If the shaft 10 is provided with two of the rollers 12, as shown, the operative end of the lever 13 will be raised positively twice during each complete rotation of this shaft 10. This results in pulling the upper strand of the belt 20 along toward the pulley 23, and causing the picker 26 positively to eject the shuttle. When that motion is completed the spring 16 yieldingly draws the parts back, except the shuttle of.

course, to the position shown, this being limited by the stop 17.

From this it will be seen that the complications which have been proposed heretofore are very largely done away with. An exceedingly simple device is secured for operating the picker, eliminating the usual picker stick, power strap and certain connected parts, which are of short durability in practice. For these are substituted the lever 13 which is not nearly as readily destructible as the usual picker stick and can be made comparatively heavy and strong and consequently has a very great comparative durability. The belt or flexible connection is also added. If made of rope it is very cheap and if made of leather or a metallic chain is more durable. In either case it involves decided advantages either in first cost or in total cost for a definite period of time over the parts which are displaced in the ordinary loom. Furthermore, when necessary to replace it, it can be done in a very simple manner as the removal of the old belt is done almost in an instant and the placing of the new one is a very short operation.

Although we have illustrated and described only a single embodiment of the invention we are aware of the fact that many modifications can be made therein by any person skilled in the art without departing from the scope of the invention as expressed in the claims. Therefore we do not wish to be limited to all the details of construction herein shown and described, but

What we do claim is:—

1. In a picking motion for a loom, the combination with a shuttle box, of a single flexible connection, means for guiding said flexible connection to move parallel with the length of the shuttle box, an arm fixed to said flexible connection and extending into the shuttle box, a picker on said arm for engaging the shuttle, the two ends of said flexible connection extending from the shuttle box in the same general direction and one of them having a guide around which it passes so that its extreme end projects in the opposite direction from the other end, a lever to which both ends of said flexible connection are secured, to positively cause the connection to reciprocate longitudinally in both directions and means for oscillating said lever.

2. In a picking motion for one end of a loom, the combination with a shuttle box, of a flexible connection having a portion thereof located parallel with the length of the shuttle box, a picker connected with said portion of the flexible connection to move therewith and extending into the shuttle box for the purpose of engaging the end of a shuttle therein, said flexible connection having its two ends extending downwardly therefrom, and one of them having a guide

around which it passes so that at the extreme end it extends upwardly and vertically, a reciprocable lever to which both ends of the flexible connection are secured, means for positively moving said end of the lever in a direction to cause the picker to eject the shuttle from the box, and yielding means for moving the lever in the opposite direction.

3. In a picking motion for a loom, the combination of a lever mounted to oscillate, a spring for normally holding the lever down, a rotatable shaft, means on said shaft for engaging the lever and elevating the operative end of the lever in opposition to said spring, a pulley located below the operative end of the lever on one side, two pulleys located above the operative end of the lever, a fourth pulley located substantially in the plane of the last two pulleys and at substantially the same elevation as one of them, a flexible connection having both ends secured to the lever, one end passing downwardly therefrom around the first named pulley, the connection extending upwardly on both sides and over the two pulleys and then around the last named pulley, a picker secured to the strand of the flexible connection between the last named pulley and one of the two pulleys, and a shuttle box into which said picker extends.

4. In a picking motion for one end of a loom, the combination of a lever mounted to oscillate on a horizontal transverse axis, a spring for normally holding the lever down, a rotatable shaft, means on said shaft for engaging the lever twice during each revolution and elevating the operative end of the lever in opposition to said spring, an adjustable stop projecting from the bottom of said lever for limiting its downward motion caused by the spring, a pulley located below the operative end of the lever on one side, two pulleys located above the operative end of the lever, a fourth pulley located substantially in the plane of the last two pulleys and at substantially the same elevation as one of them, all of said pulleys being mounted to rotate on axes substantially parallel with the plane in which the lever oscillates, a flexible connection having both ends secured to the lever, one end passing downwardly therefrom around the first named pulley, the connection extending upwardly on both sides and over the two pulleys and then around the last named pulley, a picker secured to the strand of the flexible connection between the last named pulley and one of the two pulleys, and a shuttle box into which said picker extends, the length of the shuttle box being parallel with the strands of the flexible connection with which the picker is connected.

5. In a picking motion for a loom the combination of a lever mounted to oscillate on a

- transverse axis, a spring for normally holding the lever down, a rotatable shaft, means on said shaft for engaging the lever a plurality of times during each revolution and 5 moving the operative end of the lever in opposition to said spring, a flexible connection having both ends secured to said lever, one end extending therefrom in one direction, and the other in the opposite direction and 10 both strands of the flexible connection then extending in the same general direction, means for guiding said flexible connection and holding it, a picker secured to one strand of the flexible connection and a shuttle box 15 into which the picker extends.
6. In a picking motion for a loom the combination of a lever mounted to oscillate, a pulley located beyond the operative end of the lever on one side, two pulleys located 20 on the other side of the operative end of the
- lever, a fourth pulley located substantially in the plane of the last two pulleys and at substantially the same distance from the lever as one of them, a flexible connection having both ends secured to the lever, one 25 end passing beyond the same around the first named pulley and then back by the lever to one of said two pulleys and then around the last named pulley, the other end of said flexible connection passing from the 30 last named pulley over the other of said two pulleys and back to the lever, and a picker secured to the flexible connection between the said last named pulley and one of said two pulleys. 35

In testimony whereof we have hereunto set our hands.

JOSEPH STOTT.
WILLIAM STOTT.
